BICYCLE STAND

Randall N. Johnson, 5947 Poplar St.,
Commerce City, Colo. 80022

Filed Aug. 23, 1972, Ser. No. 283,223

Term of patent 14 years

Int. Cl. D8—99; D12—11
U.S. Cl. D12—115

The figure is a perspective view of a bicycle stand showing my new design, with the chains being broken away to indicate intermediate length.

I claim:

The ornamental design for a bicycle stand, as shown and described.
